UNITED STATES PATENT OFFICE

106,003

DESIGN FOR A SHOE

Samuel Weinstat, New York, N. Y., assignor to
Bancroft Walker Company, Waltham, Mass.,
a corporation of Massachusetts

Application July 25, 1936, Serial No. 64,038

Term of patent 3½ years

To all whom it may concern:

Be it known that I, Samuel Weinstat, a citizen of the United States, residing at New York, in the county of New York and State of New York, have invented a new, original, and ornamental Design for a Shoe, of which the following is a specification, reference being had to the accompanying drawing, forming a part thereof, in which

Fig. 1 is a plan view of a shoe showing my new design, and

Fig. 2 is a view of the shoe in side elevation, the heel being shown conventionally in dotted lines.

The ribbon bow shown in Fig. 2 is omitted in Fig. 1 for clarity of illustration.

The dominant feature of my design resides in a vamp comprising a tip with a reentrant recess in its rear edge, two elongated pieces crossing the vamp diagonally and having rearwardly extending wings adjacent to the sole of the shoe, and forming reentrant angles, and quarters having forwardly inclined strap portions crossing said elongated pieces in such position as to form a rectangular opening at each side of the vamp.

I claim:

The ornamental design for a shoe substantially as shown and described.

SAMUEL WEINSTAT.
